UNITED STATES PATENT OFFICE.

JOSEPH MUIR, OF NEW YORK, N. Y., ASSIGNOR TO THE RADIUM EMANATION CORPORATION, A CORPORATION OF DELAWARE.

SHIPPING CONTAINER AND STERILIZER.

Application filed June 3, 1924. Serial No. 717,605.

To all whom it may concern:

Be it known that I, JOSEPH MUIR, a citizen of the United States, residing at New York city, State of New York, have invented 5 certain new and useful Improvements in Shipping Containers and Sterilizers, of which the following is a specification.

This invention relates to a combined shipping container and sterilizer and more particularly to an article for employment in the 10 shipping and sterilization of radium emanation seeds.

One of the objects of the present invention is to provide a container in which radium emanation seeds may be shipped with 15 safety to those handling the shipment during the period of its transportation, thereby avoiding the injurious results which might follow from a careless packing of the shipment.

Prior to implantation of the seeds in a lesion to be treated, the seeds must be sterilized. It is, therefore, another important 25 object of the present invention to provide a container so constructed that when it has reached its destination and occasion arises for the use of the contents, the said container may be employed as a sterilizer, thus obviating unnecessary handling of the emanation seeds and affording safety to the physician employing the same.

Another important object of the invention is to so construct the container that when it is initially opened, after having reached 35 its destination, there will be no likelihood of the radium emanation seeds being spilled from the container.

Another object of the invention is to so 40 construct the container that water may freely circulate through the section thereof which is to be employed as a sterilizer, and may be effectually and completely drained therefrom after the sterilization has been effected.

Another object of the invention is to provide a combined shipping container and sterilizer, especially designed for the purposes 45 above outlined, which article will be simple in construction and comparatively inexpensive to manufacture and may be employed repeatedly for its original purpose and without the necessity of renewing or replacing any of the parts.

In the accompanying drawings:

Figure 1 is a perspective view of the com-

bined shipping container and sterilizer embodying the present invention;

Figure 2 is a detail diametric sectional view through the container and sterilizer;

Figure 3 is a plan view of the sterilizer 60 or body section of the article with the cover removed and with a portion of the foraminous closure for the said section partly broken away;

Figure 4 is a plan view looking at the 65 under side of the said foraminous closure for the sterilizer section of the article.

The article embodying the present invention comprises essentially, two sections, one 70 of which is indicated in general by the numeral 1 and the other by the numeral 2. The section 1 constitutes both a container section and a sterilizing section, and the section 2 constitutes a closure for the section 1. Both

of the sections are made of metal and are 75 exteriorly of substantially cylindrical form. The section 1 is provided in its upper side with a pocket indicated by the numeral 3 in which the radium emanation seeds to be shipped are deposited. Thus the section 1

constitutes a container and by reference to 80 Figure 2 it will be observed that the pocket 3 is located concentrically of the said section 1 in which it is formed and is of a diameter considerably less than the external diameter of the said section so that the wall of the

pocket, indicated by the numeral 4, is relatively thick. Likewise the pocket is of such depth in proportion to the thickness of the section 1 that the bottom of the pocket is 85 spaced considerably above the under side of the said section 1 so that the bottom wall of the container indicated by the numeral 5, is likewise relatively thick. The thickness of these walls insures protection to

those handling the container during the 90 period of transportation as well as to those who handle the container after it has received the seeds, and those handling it after it has reached its destination and before the 95 container is opened.

The upper portion of the wall 4 of the 100 container and sterilizing section 1 is exteriorly reduced in diameter and threaded as indicated by the numeral 6. The cover section 2 of the article comprises a top 7 which is relatively thick and is provided upon its underside with a depending circumferential rim 8 which is interiorly threaded, as at 9, 105 thus adapting the cover section for removable

application to the container and sterilizer section 1. The thickness of the top 7 of the cover section 2 and the combined thickness of the upper portion of the wall 4 and the 5 rim 8 of the sections 1 and 2, respectively, likewise insures safety to those handling the container when there are radium emanation seeds therein.

In order that the seeds deposited in the 10 container and sterilizer section 1 may be retained in the pocket 3 until required for use and may likewise be prevented from being spilled from the pocket when the cover section 2 is removed, the said container and 15 sterilizer section 1 is provided with a closure for its pocket 3, which closure is indicated in general by the numeral 10. The said closure comprises an annular body 11 which is substantially flat and is provided upon its 20 under side with a depending flange 12 slit for a portion of its circumference as indicated by the numeral 13 and vertically as at 13' so as to provide a portion 14 which is normally sprung slightly outwardly as 25 shown in Figure 4 of the drawings, the metal of which the closure is formed being of a resilient nature so that the said portion 14 may be sprung inwardly against its resiliency and to occupy the circle in which the 30 said flange 12 is located. The inner surface of the wall 4 of the container and sterilizer section 1 is formed with a circumferential recess 15 which extends about the open upper side of the pocket 3. The flange 12 is exteriorly of a diameter substantially equal to the diameter of the recess 15 so that the closure 10 is adapted to have its flange 12 fitted frictionally into the open top of the 35 pocket 3 at which time the portion 14 of the flange 12 will bear more or less firmly against the wall of the said recess 15 and thus constitute a means frictionally retaining the closure in place. The numeral 16 indicates a circular piece of wire gauze which 40 is marginally secured within the inner periphery of the member 11 of the closure and thus the closure is of a foraminous nature for a useful purpose to be presently explained. At the same time the closure 45 constitutes means for effectually preventing spilling of the radium emanation seeds from the pocket 3 at the time the cover section 2 is removed from the container and sterilizer section 1. The periphery of the member 11 50 of the closure 10 is preferably knurled as indicated by the numeral 17, so as to provide for ready removal of the said closure from the container and sterilizer section 1. Likewise the sections 1 and 2 of the article 55 are preferably exteriorly knurled as indicated, respectively by the numerals 18 and 19 so as to facilitate unthreading of the section 2 from the section 1.

For a purpose to be later described, the 60 bottom wall 5 of the container and sterilizer

section 1 is formed with one or more drain openings 20 which open through the upper and under sides of the said bottom wall 5. These openings 20 are preferably of greater diameter at their lower ends than at their 70 upper ends and in fact at their upper ends are of very small diameter, these ends communicating with the interior of the pocket 3. The increase in diameter of the openings from their upper to their lower ends is 75 preferably gradual as illustrated in Figure 2.

Assuming that all of the component parts of the device are separated one from another, the radium emanation seeds to be 80 shipped are introduced into the pocket 3 and the closure 10 is fitted to the container and sterilizer section 1, thus closing the pocket, at least to the extent that escape 85 of the emanation seeds from the pocket is prevented. The cover section 2 is then threaded onto the section 1, and the device may then be packed or wrapped for shipment. When the article reaches its destination and use is to be made of the emanation seeds, the cover section 2 is removed, without disturbing the closure 10, and the section 1 with the cover 10 assembled therewith is placed in a sterilizer. During the process of sterilization, water may freely 90 circulate within the pocket 3 through the meshes of the foraminous member 16 and likewise through the openings 20. After sterilization of the contents of the container and sterilizer section 1, the said section is 95 removed from the sterilizing bath and at the time of its removal, it being maintained in a horizontal or upright position, the water which has accumulated in the pocket 3 will drain through the openings 20. Due 100 to the enlargement of these openings in the direction of their lower ends, capillary attraction is reduced to a minimum and the discharge of all water from the pocket is 105 insured. At the time the seeds are required for use, they may be removed from the pocket 3 by first removing the closure 10.

Having thus described the invention, what is claimed as new is:

1. A combined shipping container and sterilizer comprising a container and sterilizer section having a pocket provided with an open top, a foraminous closure for the said top of the pocket having a depending flange provided with a resilient normally outwardly sprung bearing portion, the said flange being frictionally received within the open top of the pocket, and a cover section for the first-mentioned section. 115

2. A combined shipping container and sterilizer comprising a container and sterilizer section, a removable foraminous closure therefor, the said section being provided with drain openings, and a cover section for the first-mentioned section. 125

3. A combined shipping container and sterilizer comprising a container and sterilizer section, a removable foraminous closure for the said section, the said section being provided in its bottom with an opening communicating with the interior of the section and opening through the under side

of the said bottom of the section, the opening being of gradually increasing diameter from its upper to its lower ends, and a cover section for the first-mentioned section.

In testimony whereof I affix my signature.

JOSEPH MUIR. [L.S.]
